UNITED STATES PATENT OFFICE.

CLIFFORD L. FINCH, OF MINNEAPOLIS, MINNESOTA.

SIGNAL-OPERATOR FOR SPREADING RAILS.

1,383,093.

Specification of Letters Patent. Patented June 28, 1921.

Application filed February 3, 1921. Serial No. 442,139.

To all whom it may concern:

Be it known that I, CLIFFORD L. FINCH, a citizen of the United States, residing at Minneapolis, in the county of Hennepin and State of Minnesota, have invented certain new and useful Improvements in Signal-Operators for Spreading Rails, of which the following is a specification.

This invention relates to improvements in railroads, and the primary object of the invention is to provide an improved device of simple construction and positive in operation, which will preclude train wrecks caused by the spreading of rails, thereby resulting in the saving of lives and property.

A further object of the invention is the provision of an improved rail spreading alarm device, which is associated with the track rails in such a manner that when the rails spread beyond a predetermined distance from any cause, a circuit will be closed or opened, as the case may be, for operating the usual block signal mechanism, so that when a train enters the block in which the rails are spread to a danger point, a warning will be given to the engineer by said block signal mechanism.

A further object of the invention is the provision of an improved signaling device for indicating when rails are spread embodying clamp members electrically connected to the track rails and a connecting rod for said clamps, the rod being electrically insulated from one of said clamp members and adapted to make electric contact therewith when the rails are spread, thus closing or short circuiting the block in which the rails are spread, so as to permit the actuation of the ordinary block signaling mechanism.

A still further object of the invention is to provide an improved rail spreading device of the above character, which will be durable and efficient in use, one that is simple and easy to manufacture, and one which can be placed upon the market and incorporated with the ordinary block signaling mechanism of a railroad, at a minimum cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a transverse section through

an ordinary railroad track, showing the improved rail spreading signaling device, operatively connected thereto.

Fig. 2 is a fragmentary plan view of a railroad track, showing the improved rail spreading signaling device connected thereto.

Fig. 3 is an enlarged elevation of the improved rail spreading signaling device, showing parts thereof in section.

Fig. 4 is an enlarged vertical longitudinal section through a portion of the signaling device, showing the contacts arranged in their normal spaced position.

Fig. 5 is a detail perspective view of one of the contact members.

Fig. 6 is a detail perspective view of the other contact member which is associated with the connecting operating rod.

Fig. 7 is a fragmentary detail perspective view of one of the housings for a portion of the operating mechanism showing the means of connecting the housing with one of the railroad clamps, and

Fig. 8 is a diagrammatic view of the improved device connected with the usual type of block signaling mechanism.

Referring to the drawings in detail, wherein similar reference characters designate corresponding parts throughout the several views, the letter A indicates a section of a railroad track, which may be divided in the usual manner into blocks, designated by the numerals 10, 11 and 12 in Fig. 8 of the drawings, and B the improved rail spreading signal controlling device. The block signaling mechanism is designated by the letter C and is of the usual or any preferred construction and forms no part of the present invention. As stated the block signaling mechanism C is of ordinary construction, and therefore only a brief description thereof will be given.

The railroad track A is also of the usual or any preferred construction and includes spaced ties 13, and the railroad rails 14 and 15. The rails 14 and 15 at predetermined points are electrically insulated by means of suitable insulation designated by the numeral 16 in Fig. 8 of the drawings, so as to divide the track A into the different blocks 10, 11 and 12. The signal controllers B for the block signaling mechanism are arranged at predetermined points throughout the railroad track A and extend from one rail to the other. It is preferred that the signal

controllers B be positioned approximately sixteen and a half feet apart or every half rail length as the standard rail length for many railroads is 33 feet. This is purely optional and the controllers B may be arranged closer together or farther apart as may be desired.

The signal block mechanism C briefly described, consists of lead wires 17 and 18, 10 which lead from the rails 14 and 15 respectively, of each one of the blocks of the railroad, and these lead wires lead to the terminals of the electromagnets 19. The rails 14 and 15 are connected together by means 15 of a wire 20 which may have interposed therein a suitable source of electrical energy, such as a storage battery or the like 21. Thus it will be seen that the circuit through the electromagnet 19 is normally closed, so 20 that the armature 22 of the block semaphore signaling mechanism 23 will be normally held in a raised position. A wire 24 is connected to the armature and leads to the operating mechanism 25 of the semaphore 25 28 and the wire 26 leads from a stationary contact 27 to the operating mechanism 25 of the semaphore, and this wire may have interposed therein any suitable source of electrical energy indicated by the numeral 30 28. As shown the armature 22 engages the contact 27 when the magnet is energized, but that when the magnet is deenergized caused by short circuiting of the block circuit, the armature will drop away from the contact 35 27, thus allowing the semaphore mechanism to operate in the usual manner. This as stated is of the common construction, but if so desired, the track battery 21 may be interposed in either the wires 17 or 18 so that the 40 track circuit will normally be open and the magnet deenergized. In this form when any one of the controllers B is actuated by the spreading of the rails A the circuit will be closed through the magnet 19, thus attracting the armature 22 and closing the 45 block semaphore signaling mechanism 23 for operating the same.

The signal controllers B are all of the same construction, and a description of one 50 is deemed sufficient for all and as shown, each one of the controllers includes rail clamps 30 and 31, which are of identically the same construction. The rail clamp 30 is adapted to engage the rail 14, while the rail 55 clamp 31 is adapted to engage the rail 15 and each one of the clamps includes a base plate 32 having an inner hooked terminal 33 for engaging around the inner base flange of the rails. The opposite end of the base 60 plates are extended and receive a spacer block 34 to which is fitted a clamp bar 35 which engages the upper surface of the outer base flanges of the rails 14 and 15. The clamp bar 35 is held in place on the base 65 plate 32 by suitable bolts or the like 36,

The inner ends of each one of the clamp plates 35 are provided with a set screw 37 which can be adjusted into intimate contact with the outer rail flanges so as to insure of forming an electrical connection between 70 the clamps 30 and 31 and the track rails 14 and 15. Each of the base plates 32 has formed thereon the depending arms 38 and 38' respectively. The arm 38 is recessed and forms a guide for the connecting rod 39, 75 while the depending arm 38' is formed integrally with a longitudinally extending casting 40 in which is positioned the contact members 41 and 42 which will be hereinafter more specifically described.

The housing 40 is of a cylindrical shape and is provided with end caps 43 and 44, and the end cap 43 is provided with a relatively large axial opening 45, through which the connecting rod 39 is adapted to slide. The 85 opening 45 has an interior diameter which is greater than the diameter of the connecting rod 39 so that the rod will be spaced therefrom at all times. An insulating guide sleeve 46 is provided for receiving the rod 90 39 and to hold the same centered in the casing. The inner end of the insulating sleeve 46 has attached thereto the stationary contact 41, which is of annular configuration, and through which the connecting rod 39 is 95 adapted to slide. The rod has a less diameter than the internal diameter of the stationary contact 41, so that during the sliding movement of the rod, the same will not contact therewith. The contact 41 is provided 100 with outwardly extending diametrically opposed attaching ears 47, which are suitably apertured for the reception of fastening elements (not shown) by means of which the same may be secured to insulating sleeve 46. 105 This washer or contact 41 is in intimate engagement with the inner surface of the housing 40, so as to form an electrical connection therewith, the inner surface of the housing 40 inwardly of the insulating sleeve 46 is provided with a second sleeve of insulation 48, having a relatively large interior diameter, and the inner end of this sleeve 48 engages the face of the contact 41 opposite to the face 110 engaged by the insulating sleeve 46 and the outer edge of the sleeve 48 engages an insulating disk 49, which is in abutting relation to the end cap 44. The end of the connecting rod 39 which is extended into the casing 40 is provided with threads, on which are 115 threaded a pair of lock nuts 51. These lock nuts 51 are adapted to hold the movable contact 42 in position on the rod. This movable contact 42 is electrically connected with the rod 39 and as shown consists of a pair of 120 spaced washers 52 and a connecting portion 53. One of the lock nuts 51 engages between the washers 52 and the other engages the outer face of the outermost washer. The rod 39 has the end opposite to the end which is 125 130

arranged in the housing 40 provided with threads 54 and has adjustably mounted thereon suitable stop nuts 55 which are adapted to engage the inner face of the depending arm 38. The opposite face of the depending arm 38 is adapted to be engaged by a washer 56, and this washer is held in contact with the arm 38 by means of an expansion spring 57, which is coiled around 10 the rod 39. The outer end of the spring 57 engages suitable lock nuts 58. By this construction, it can be seen that when the rails 14 and 15 spread in relation to each other, the clamps 30 and 31 will be moved in opposite directions consequently pulling the casting or housing 40 in one direction and the rod 39 in the opposite direction. Thus when the movable contact 42 engages the contact 41, the rails 14 and 15 will be electrically connected. The spring 57 allows for a certain give between the two clamps 30 and 31 and thus prevent breakage of any parts of the controller B in case the rails spread beyond the point where the contacts 42 and 41 engage each other. It also can be seen that the nuts 58 and 55 also form means for adjusting the rod 39 so as to permit the contacts 42 and 41 to engage each other at a less or greater movement between the rails as may be desired. It also can be seen that the contact 42 can be initially adjusted on its end of the rod 39 so as to bring the same closer to or farther away from the contact 41.

In order to prevent the actuating parts from becoming clogged by dirt or the like and to protect the same from the elements, a casing 60 and a casing 61 are provided for the opposite ends of the rod 39 and these casings are arranged below the clamps 30 and 31. A suitable tubular casing 62 is provided for connecting the casings 60 and 61 and forms means for housing the connecting rod 39. Each one of the casings 60 and 61 includes a bottom wall 63, side and end walls 64 and a top wall 65. The top wall 65 is made into two sections, a rigid section 66 and a movable section 67. The movable sections 67 are riveted or otherwise secured to the depending arms 38 and 38' respectively and the longitudinal edges thereof are provided with guide flanges 68. These guide flanges 68 may be connected with the side walls 64 of the casings 60 and 61 by means of a slot and pin connection 69.

In operation of the improved device, if the rails 14 and 15 spread from any cause, the rod 39 and the casing 40 will be moved in opposite directions as heretofore stated, thus moving the contact 42 into engagement 55 with the contact 41, thus electrically connecting the rails 14 and 15 together. This will cause the short circuiting of the track circuit, as the current will flow from one terminal of the battery 21 through one rail,

through the controller B to the opposite rail and then back to the battery. This will cause the deenergizing of the magnet 19 and the opening of the semaphore block signaling operating mechanism, which will move the semaphore arm 23 to a danger position 70 thus indicating to the engineer of the train riding into the block that the rails are spread and that danger is to be encountered in the block.

From the foregoing, it can be seen that 75 an improved and simple device has been provided, for effectively indicating when rails are spread, thereby preventing the loss of life and property. This device also effectively eliminates the necessity of providing men for walking tracks to see if the same are in good condition, as the device will effectively indicate when any change in the normal condition of the track takes place.

Changes in details may be made without departing from the spirit or scope of this invention, but—

I claim:

1. In a railway signal apparatus, the combination with an electrically operated danger signal, of a rail connecting device including a pair of normally spaced contacts electrically connected to opposite rails and means for permitting the engagement of the contacts for electrically connecting the rails to set the signal to danger when the rails become moved laterally a predetermined distance from their normal position.

2. In a railway signal apparatus, the combination with an electrically operated danger signal, of a rail connecting device including clamps secured to the rail and electrically connected therewith, a rod connected to one of said clamps, a housing connected with the other clamp and arranged to slidably receive one end of said rod, and a contact electrically connected to the housing, a contact carried by the rod and arranged to move into engagement with the first mentioned contact for electrically connecting the rails to set the signal to danger, when the rails become moved laterally a predetermined distance from their normal position.

3. In a railway signal apparatus, the combination with an electrically operated danger signal, of a rail connecting device including a pair of clamps detachably connected to the opposite rails, a rod carried by one of said clamps and electrically connected therewith, means for permitting a limited movement between the rod and said clamp, a housing carried by the other clamp arranged to slidably receive one end of the rod, a stationary contact electrically connected to the housing, a movable contact carried by the rod and electrically connected there-

to, the rod and housing being adapted to move in opposite directions upon the spreading of the rails, whereby the contacts will be moved into engagement with each other 5 for electrically connecting the rails to set the signal to danger.

4. In a railway block signal apparatus, the combination with an electrically operated danger signal, of a rail connecting device 10 including a pair of clamps electrically connected to the rails, depending arms formed on the clamps, a rod slidably carried by one of the arms, a stop member adjustably carried by the rod arranged to engage one face of the last mentioned arm, an expansion spring coiled around said rod arranged to engage the opposite face of said last mentioned arm, an adjustable member fitted on said rod arranged to engage the outer end of said spring, a housing carried by the arm of the other clamp arranged to slidably receive the rod, means for insulating the rod from said housing, a contact carried by the housing electrically connected 25 thereto, a contact carried by the rod electrically connected thereto, the contacts being adapted to be moved into engagement with each other upon the spreading of the rails for electrically connecting the rails together, 30 to set the signal to a danger position.

5. In a rail spreading signal, the combination with a railroad track including supporting ties, a pair of rails, of a rail connecting device including a pair of clamps 35 electrically connected with the rails, depending arms formed on the clamps, a rod connected to one of said arms, a housing connected to the other of said arms and arranged to slidably receive the rod, a contact member carried by the rod and electrically connected thereto, and a contact member carried by the housing and electrically connected thereto, whereby upon movement of the rails out of their normal position the

contacts will be moved into engagement with each other.

6. As a new article of manufacture, a rail connecting device including a pair of rail engaging clamps, a rod slidably and electrically connected to one of the clamps, a 50 housing carried by the other clamp and arranged to slidably receive the rod, and spaced contacts carried by the rod and housing.

7. As a new article of manufacture, a rail connecting device including a pair of clamps, each consisting of a base plate for engaging the lower face of the rails, a clamping jaw formed on one edge of the base plate for engaging one base flange of the rails, a clamp- 60 ing plate carried by the base plate for engaging the opposite base flange of the rails, depending arms formed on the base plates, a housing rigidly carried by one of said arms, the other of said arms being apertured, 65 a rod slidably mounted through said apertured arm and slidably mounted in said housing, a stop member carried by said rod and arranged to engage one face of the apertured arm, an expansion spring coiled 70 around said rod and arranged to engage the opposite face of said apertured arm, adjustable stop members carried by the rod and arranged to engage the outer end of said expansion spring, a contact carried by the rod, 75 and a contact carried by said housing.

8. In an operating device for rail spreading signals, a sliding rod, a tubular housing arranged to receive one end of the rod, an insulating sleeve arranged in the housing 80 and supporting said rod, a washer electrically connected to the rod and insulated from said housing, and a washer insulated from said rod and electrically connected to said housing and adapted to contact with the 85 rod carried contact upon movement of the rod and housing in opposite directions.

CLIFFORD L. FINCH.
